UNITED STATES PATENT OFFICE.

CHARLES WALTERS, OF CHICAGO, ILLINOIS, ASSIGNOR OF ONE-HALF TO WILLIAM P. OWENS.

WATER HEATER.

Application filed May 15, 1918. Serial No. 234,593.

To all whom it may concern:

Be it known that I, CHARLES WALTERS, a citizen of the United States, and a resident of the city of Chicago, county of Cook, and State of Illinois, have invented certain new and useful Improvements in a Water Heater; and I do hereby declare that the following is a full, clear, and exact description of the same, reference being had to the accompanying drawings, and to the numerals of reference marked thereon, which form a part of this specification.

In practically all water heaters of the burner and coil type, the cold water to be heated is admitted at the lower end of the water coil and passes upwardly through the coil to be heated by means of air which is drawn into the lower portion of the heater to be heated by the burner, and is then caused to rise in the heater around the water coil and be drawn out through a flue or draft pipe connected to the upper portion or end of the water heater to cause a forced draft therethrough. A great amount of heat is thus wasted due to the fact that the heated air only acts in its upward passage through the heater to heat the water, and is then exhausted while still containing sufficient heat units adapted for further heating.

This invention relates to an improved form of a water heater wherein the air which is heated by a burner is permitted to pass upwardly through a water coil and then pass downwardly around the water coil to be exhausted from the lower portion of the heater without forced draft to thoroughly heat the water and afford an arrangement whereby the heated air acts in both its upward and downward passage through the heater to utilize substantially all the heat units in the heated air before it is permitted to be exhausted from the lower portion of the heater.

It is an object of this invention to construct a water heater wherein the circulating air after heating the water is permitted to escape through the lower portion of the heater without forced draft.

Another object of the invention is the construction of a water heater wherein an opening is provided in the lower portion of the heater to check the draft to permit substantially all of the heat units in the heated air circulating in the heater to be

utilized before the air is exhausted through the lower portion of the heater.

It is also an object of the invention to construct a water heater wherein the loops of the water coil are disposed closely together to permit heated air to pass upwardly through the coil and then downwardly therearound to utilize practically all of the heat units in the heated air for heating the water circulating in the coil before the air is permitted to escape from an air outlet pipe positioned at the lower portion of the heater.

It is an important object of the invention to construct a water heater wherein the heated air is caused to circulate upwardly through and downwardly around a water coil to heat the water therein before the air is permitted to leave the lower portion of the heater through an exhaust pipe wherein the draft has been checked.

Other and further important objects of this invention will be apparent from the disclosures in the specification and drawings.

The invention (in a preferred form) is illustrated in the drawings and hereinafter more fully described.

On the drawings:

Figure 1 is a front elevation of a water heater embodying the principles of this invention and showing parts broken away to show the interior construction.

Figure 2 is a section taken on line 2-2, of Figure 1, with parts in elevation.

Figure 3 is an enlarged section taken on line 3-3 of Figure 2.

Figure 4 is an enlarged section taken on line 4-4, of Figure 2, with parts omitted.

As shown on the drawings:

The reference numeral 1, indicates a base or support provided with a plurality of air intake openings 2, in the sides thereof, and having integrally formed therein a flange ring 3, to receive seated thereon the apertured bottom or base plate 4, of an outer casing or housing 5, which is closed at its upper end. Provided in the lower front portion of the casing 5, is a door 6, adapted to permit lighting of a large gas burner 7, which is securely mounted centrally in the base plate 4, and is connected with a gas supply pipe 8, equipped with a suitable valve 9, on the exterior of the heater.

Rigidly secured horizontally within the outer casing 5, directly above the door 6, is a centrally apertured partition plate 10, having rigidly secured in the opening thereof of a downwardly directed outward flaring hood 11, which is disposed directly over the burner 7. Disposed centrally or axially within the outer casing 5, is a vertical-sleeve pipe, cylinder or inner casing 12, the lower end of which rests upon the partition plate 11, surrounding the central opening therein, and having a portion thereof removed from the lower front side thereof to afford an opening 13. The upper end of the sleeve 12, which is open, is closed by means of a cover or cap 14, which engages around the upper end of the sleeve and is suspended in position from the top of the outer casing by means of a screw bolt 15.

Projecting into a suitable opening provided in the rear of the outer casing directly above the partition plate 10, is one end of an air outlet or exhaust pipe 16. Provided in the partition plate 10, directly in front of the inner open end of the exhaust pipe 16, is an opening 17, acting to check any draft through the exhaust pipe 16.

A water coil 18, is disposed vertically within the sleeve 12, and has the loops thereof of closely seated one on the other to prevent air from passing therebetween. The lower loops of the water coil project into the hood 11, and terminate in a straight pipe 19, which connects up with a cold water supply pipe 20. The uppermost loops of the coil are separated and loop around within one another and terminate in a straight pipe 21, which projects upwardly through the cap 14, and the top of the outer casing 5, to connect up with any hot water pipe system.

The operation is as follows:

By opening the gas valve 9, gas is supplied to the burner 7, which is lighted through the door 6, thereby causing the air surrounding the burner to be heated. The heated air rises, and due to the arrangement of the water coil the heated air passes upwardly through the coil to heat the water circulating upwardly therethrough. The upper end of the sleeve 12, is closed by the cap 14, which acts to deflect the heated air downwardly around the upper separated loops of the coil and further causes the heated air to pass downwardly around the outer portion of the coil to set up a circulation of heated air as indicated by the arrows. The heated air reaching the lower end of the sleeve 12, on the exterior of the coil 18, passes through the opening 13, into the space afforded between the sleeve 12 and the inner walls of the casing 5, and then passes outwardly or is exhausted through the pipe 16. The opening 17, is provided in the plate 10, to check any draft or forced

suction in the exhaust pipe 16. An arrangement is thus afforded whereby the heated air within the heater utilizes substantially all of its heat units to heat the water circulating in the coil 18, both as said heated air passes upwardly through the coil and as it passes downwardly around the exterior of the coil. The water heater is thus highly efficient and results in a minimum waste of heat, since the air passing outwardly through the exhaust pipe 16, has practically exerted a heating effect upon the water in the coil during the entire upward and downward passage of the air through the sleeve 12.

The tight or close arrangement of the loops of the coil 18, prevents the heated air from passing therebetween until the upper end of the coil is reached, and since there is no forced draft or suction in the heater the heated air does not readily pass from the heater. The coil 18, being heated from both sides causes the water flowing in the coil pipes to be rapidly heated, thereby producing a water heater of simple and effective design wherein the heated air circulates through the heater and is exhausted without suction or forced draft through the lower portion of the heater.

I am aware that numerous details of construction may be varied through a wide range without departing from the principles of this invention, and I therefore do not purpose limiting the patent granted otherwise than necessitated by the prior art.

I claim as my invention:

1. A water heater embracing an outer casing, a burner therein, an apertured partition wall in said casing above said burner, a downwardly directed hood connected in said partition wall above said burner, a water coil in said casing projecting into said hood, an inner casing for enclosing said water coil having an opening in the lower portion thereof, said burner adapted to heat the air in said inner casing to cause the heated air to rise in said coil and be deflected downwardly by the closed upper end of said inner casing to cause said heated air to heat the water in said coil both by the upward and downward movement of said heated air, a waste gas exhaust pipe connected with the lower portion of said outer casing above said partition wall to afford a means for the escape of the spent gases passing through the opening in the inner casing, said partition wall having an opening therein adapted to afford a means for checking the draft in said air exhaust pipe.

2. In a water heater of the class described, an outer casing, a water coil therein having the lower loops thereof closely associated one with the other to prevent air from passing therebetween and the upper loops separated, a heater for heating the coil in said

casing, a closed inner casing enclosing said coil and adapted to cause the heated air to pass upwardly through said coil and then downwardly around said coil to heat the 5 water, a waste gas exhaust pipe connected to the lower portion of the outer casing, and a plate supporting said inner casing and having an opening therein to check the draft in said exhaust pipe.

- 10 3. In a water heater of the class described, an outer casing, a partition plate secured in the lower portion thereof, a water coil disposed within said outer casing projecting downwardly through said partition plate, a 15 burner therebelow, a closed inner casing on said partition plate enclosing said coil and having an opening in the lower side portion thereof, said burner adapted to heat the air in the heater to cause the heated air

to pass upwardly and then downwardly 20 around said coil within said inner casing to heat the water passing through said coil, and a waste gas exhaust pipe connected in the lower portion of said outer casing above 25 said partition plate to permit the spent gases issuing from the opening in said inner casing to pass outwardly through said exhaust pipe, said partition plate provided with an opening below the inner end of said exhaust pipe for checking any draft therein. 30

In testimony whereof I have hereunto subscribed my name in the presence of two subscribing witnesses.
